[57] CLAIM

The ornamental design for a handbag, as shown and described.

DESCRIPTION

FIG. 1 is a front perspective view of a handbag showing my new design with the front flap in a raised position; FIG. 2 is a bottom rear perspective view thereof; FIG. 3 is a right end elevational view thereof, portions of the front flap and carrying straps being broken away and omitted for convenience of illustration; and FIG. 4 is a top perspective view of the handbag in an open condition, a portion of one of the carrying straps being broken away and omitted for convenience of illustration.
